(57) **CLAIM**

The ornamental design for an atomizer for electronic cigarette as shown and described.

DESCRIPTION

FIG. 1 is a front, top and right side perspective view of an atomizer for electronic cigarette showing our new design; FIG. 2 is a rear, bottom and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 2.

The evenly-spaced broken lines depict portions of the atomizer for electronic cigarette that form no part of the claimed design; the dot-dash broken lines in FIGS. 1, 2, 9 and 10 are for purposes of annotating the enlarged view only and form no part of the claimed design.
